UNITED STATES PATENT OFFICE

KARL BOLLMANN, OF ZURICH, SWITZERLAND, ASSIGNOR TO LANDIS AND GYR, A-G., A CORPORATION OF SWITZERLAND

ELECTROMAGNET

Application filed May 22, 1930, Serial No. 454,716, and in Switzerland July 2, 1929.

The invention relates to novel and useful improvements in electro-magnets and more especially to such improvements in devices for connecting the ends of fine wire magnet 5 windings, such as those of electricity meters, to the relatively heavy power circuit wires or other outside connections.

Objects and advantages of the invention will be set forth in part hereinafter and in 10 part will be obvious herefrom, the same being realized and attained by means of the instrumentalities and combinations pointed out in the appended claim.

The invention consists in the novel parts, 15 constructions, arrangements, combinations and improvements herein shown and described.

The accompanying drawing, referred to herein and constituting a part hereof, illustrates one embodiment of the invention, and together with the description, serves to explain the principles of the invention.

Of the drawing:—

Fig. 1 is an elevation of one embodiment of 25 the invention;

Fig. 2 is a side elevation, looking at Fig. 1 from the left;

Fig. 3 is an elevation of a meter, showing a modified form of the invention;

20 Figs. 4, 5 and 6 show another modified form of the invention; and

Figs. 7 and 8 likewise show other modified forms of the invention.

While several modified forms of construction embodying the invention are shown in the drawing, it will be understood that such showing is exemplary, and is not restrictive as to the possible number of forms which may be designed while still utilizing the novel 40 principles of the present invention.

The invention in certain of its aspects is especially applicable to electro-magnets which have relatively fine wire windings, such as electricity meter magnets, wherein 45 the ends of the fine wire for the coils are connected to relatively heavy power line wires or the like.

By my invention coil wire and line wire connecting means are provided which are 50 immune to breakage of the circuit, or other

disturbances, which are simple as to mounting and connection, and inexpensive to manufacture and install. To this end, there is provided a connection between the coil and line wires which is firmly fixed to the exterior of the coil and protects the connection against rupture or damage either by tensional or lateral strains. 55

Referring now in detail to the various forms shown by way of example in the accompanying drawing, the Figures 1 and 2 show a connection device, which consists in its details of two clamping pieces 1, 2 which take up the pull of the connecting cables, or line wires, and an insulating plate 3 which consists of paper, fiber, or other suitable material, carrying the clamping pieces 1, 2. The clamping pieces 1, 2 are passed through apertures 4 in the insulating plate 3 (which apertures are shown in a somewhat similar 70 construction in Figure 5), and are thereby firmly connected therewith. The insulating plate 3 is firmly connected to a coil 8 by any means, such as a band 7, consisting for example of cotton thread. The band 7 passes 75 about the coil 8, and is firmly fixed thereto. The clamps 1 and 2 have two lateral lugs 5, 6 formed into a channel-shaped eye. The ends of the wires 9, 10 of the bobbin are passed through corresponding openings 11, 12 in 80 the insulating plate 3, and are wound respectively into small wire spirals 13 and 14.

In making the connection, the ends of the cable conductors 15 and 16 are placed within the lugs 5, 6, which are pressed together, 85 whereby the cable conductors are clamped fast, and the free ends 17, 18 of the cables 15, 16 are within the helical ends 13, 14 of the coil wires. A permanent electrical connection is made between the line wire ends 17, 90 18 and the coil wire ends 13, 14, preferably by soldering. Thus the ends of the power wires are firmly and simply held on the exterior of the coil, and the ends of the coil wires are fixed thereto, without danger of 95 any strain coming on the connection.

Figure 3 shows a different form of connection. In this form, the ends of the line wire cables 15, 16 are secured against movement relatively to the coil by bending back 100

- upon themselves the ends 19, 20 of the clamping pieces 1, 2 (mounted on the insulating plate 3). Eyes 21 and 22 are formed integral with the respective clamping pieces 1, 2. The ends of the coil wires 9, 10 are passed through eyes 21 and 22, and the ends 17, 18 of the cables 15, 16 are clamped within the turned over ends 19 and 20 of plates 1 and 2; and are connected together by soldering.
- 10 In Figures 4 to 6 there is shown a coil with flat connecting conductors, which are used simultaneously for the clamping of the connecting cables. The flat conductors 23, 24 are connected to the inner and outer ends of the coil winding, and are passed through the holes 4 in the insulating plate 3 (Figure 5) and then brought back again forming loops 25 and 26. The band 7 is wound over and about the bent-back ends 27, 28 of the two flat conductors 23, 24. After passing the conductor cables 15, 16 through the loops 25, 26, the latter are pressed together, and the ends 27, 28 of the flat conductors 23, 24 soldered to the conducting wires 17, 18 of the cables 15, 16.

Two simplified constructional forms of connections are shown in Figures 7 and 8, wherein only a single clamping piece 29 is employed. In Figure 7 the clamping of the conductor cables 15, 16 is effected by simply bending around one end 30 of a clamping piece 29, connected to the winding 8 of the coil by a band 7. The other end 31 of the clamping piece 29 is bent around on to the band 7, whereby a more secure hold of the clamping piece 29 on the band 7 is effected. In Figure 8 the clamping piece 29, which is held by two bands 7, 32, has two lugs 33, 34 clamping the connecting cables 15, 16 laterally. The conductor ends 17, 18 of the connecting cables 15, 16 and the ends of the bobbin, made in the form of flat conductors 23, 24, are secured together by soldering.

11 The invention in its broader aspects is not limited to the specific mechanisms shown and described but departures may be made therefrom within the scope of the accompanying claim without departing from the principles of the invention and without sacrificing its chief advantages.

What I claim is:—

An electric coil having a connection with the line circuit including means for electrically connecting the relatively heavy line wires to the relatively fine coil wires, a clamping device for independently securing the line wires to the coil so as to take any pull thereon, and means for separately attaching the clamping device to the coil comprising a band embracing the coil and clamping device but lying between the line wires and said clamping device.

In testimony whereof, I have signed my name to this specification.

KARL BOLLMANN.
